SWITCH CONSTRUCTION

Hugh A. Triplett, Wilmette, Ill., assignor to
Schweitzer & Conrad, Inc., Chicago, Ill., a corporation of Delaware

Application August 2, 1940, Serial No. 349,709

11 Claims. (Cl. 200—149)

This invention relates, generally, to electric switches, and it has particular relation to switches that are provided with means for extinguishing arcs drawn on operation thereof.

An object of this invention is to provide arc extinguishing means which will evolve an arc extinguishing medium when subjected to the heat of an arc and which will be substantially unaffected by moisture in the atmosphere and will maintain its shape without warping.

Another object of this invention is to provide arc extinguishing means in the form of rings of fiber stacked one above the other.

Still another object of this invention is to prevent warping of the rings of fiber by stacking them so that the grains in the rings run in different directions.

Still another object of this invention is to provide for extinguishing an arc in a switch between the inner surface of a sleeve and the outer surface of a plug of insulation.

It is another object of this invention to form the sleeve of insulation by a stack of fiber rings.

It is another object of this invention to provide for extinguishing the arc drawn on separation of a plug-like switch member from a cooperating metallic sleeve by drawing the arc in the space between a sleeve and plug of insulation.

Other objects of this invention will, in part, be obvious and in part appear hereinafter.

For a more complete understanding of the nature and scope of this invention, reference may be had to the following detailed description, taken in connection with the accompanying drawings in which:

Figure 1 is a view, in front elevation, of a circuit interrupter in which the present invention is embodied;

Figure 2 is a detail sectional view, at an enlarged scale, taken along the line 2—2 of Figure 1;

Figure 3 is a detail sectional view, at an enlarged scale, taken along the line 3—3 of Figure 1 but showing the switch members in the switch closed position;

Figure 4 is a perspective view of some of the fiber rings illustrating how they are stacked;

Figure 5 is a detail sectional view, taken along the line 5—5 of Figure 1, but showing the switch members in the switch closed position;

Figure 6 is a longitudinal sectional view of an alternate switch construction to that shown in Figure 3;

Figure 7 is a detail sectional view taken along the line 7—7 of Figure 6;

Figure 8 is a longitudinal sectional view illus-

trating another embodiment of the invention; and

Figure 9 is a detail sectional view taken along the line 9—9 of Figure 8.

Referring now particularly to Figure 1 of the drawings, it will be observed that the reference character 10 designates a suitable support for stationarily mounting insulating cross members 11 between which are clamped insulating sleeves 12 which have extensions 13. Between each pair of sleeves 12 and 13 there is positioned a metallic plate 14 having an extension 15 that permits connection of a line conductor thereto. The metallic plates 14 are also provided with pairs of generally U-shaped switch members, Figure 5, each of which is arranged to receive a pair of spring contact fingers 17. The contact fingers 17 are mounted on and electrically interconnected by a metallic yoke 18 that is carried on a suitable support member 19 extending from a conventional type operating mechanism 20. It will be understood that the support member 19 is movable vertically under the control of the operating mechanism 20 in order to operate the switch to the closed and open positions.

In Figure 3 of the drawings are shown the details of construction of one of the pairs of cooperating switch members provided with arc extinguishing means in accordance with this invention. As there illustrated, a metallic sleeve 24, which forms a generally cylindrical stationary switch member, is threaded into the metallic plate 14. The lower end of the insulating sleeve 12 and the upper end of the extension 13 are threaded, as shown, onto the ends of the cylindrical switch member 24.

The cylindrical switch member 24 is provided at its lower end with an inwardly extending contact section 25 for engaging contact fingers 26 which form a part of a movable plug-like switch member. The contact fingers 26 are integrally formed with a metallic sleeve 27 that is threaded onto a metallic rod 28 the lower end of which extends through suitable flanged washers 29 and is clamped by suitable means, such as a nut, to the end of the yoke 18. A sleeve 30 of insulation surrounds the portion of the rod 28 between the lower surface of the metallic sleeve 27 and the top of the upper flange washer 29.

The plug-like switch member formed by the contact fingers 26 is arranged to move through a bore 31 that is formed in a sleeve of insulation made up by fiber washers 32 stacked one above the other.

The washers 32 are formed of fiber because this material evolves water vapor when subjected to

the heat of an arc which assists in deionizing the arc space and tends to prevent re-striking as well as assisting in extinguishing the arc. The fiber in the form of washers is employed instead of a continuous sleeve of fiber in order to minimize warping. When a continuous tube of fiber is subjected to the moisture in the atmosphere, it tends to warp. In many instances the slight warping of the fiber tube which takes place may be unimportant because close clearances are not involved. However, where close clearances are involved and it is desired to maintain the diameter of the bore 31 substantially uniform throughout the life of the apparatus, it is preferable to employ a stack of fiber washers 32. In order to further minimize the effects of warping, the washers 32, as shown in Figure 4 of the drawings, are stacked so that the grains, as indicated by the arrows 33 and 34, run in different directions in adjacent washers.

It will be noted that the stack of fiber washers 32 is located within the extension 13 and is held against the under side of the cylindrical switch member 24 by means of a nut 35 that is threaded into the lower end of the extension 13.

It will be understood that, when the plug-like switch member formed by the contact fingers 26 moves downwardly and out of engagement with the contact portion 25 of the cylindrical switch member 24, an arc will be drawn therebetween if the circuit in which the switch is connected has current flowing therein. This arc will play upon the bore 31 and, as described, will evolve therefrom an arc extinguishing medium. It is desirable to further confine the arc. For this purpose, a plug of insulation in the form of a stack of fiber washers 37 is arranged to be moved into the bore 31 so that the arc is confined between the convex outer surface 38 of the washers 37 and the bore 31. The plug is formed by the stack of fiber washers at 37 for the same reason that the sleeve is formed by the stack of fiber washers 32.

It will be observed that the stack of fiber washers 37 is mounted on a sleeve of insulation 39 which has a flanged head 40. The sleeve of insulation 39 is threaded at its lower end on an integrally formed threaded portion 41 of the rod 28. A metallic washer 42 is interposed between the lowermost fiber ring 37 and the upper end of the rod 28.

When the switch construction just described is operated to the open circuit position under the control of the operating mechanism 20, the contact fingers 17 first move out of engagement with the U-shaped switch members 16, Figure 5. The entire flow of current then is between the cylindrical switch member 24 and the plug-like switch member formed by the contact fingers 26 in each of the switch units. Continued downward movement of the yoke 18 and the rod 28 finally causes the contact fingers 26 to separate from the contact portion 25 of the cylindrical switch member 24 and, as previously described, an arc is drawn therebetween. This arc plays upon the bore 36 of the fiber washers 32 and evolves therefrom the arc extinguishing medium. The contact fingers 26 move downwardly through the bore 31 and are followed by the plug of insulation formed by the fiber washers 37. The arc is then confined between the outer surface 38 of the fiber washers 37 and the bore 31 and is quickly extinguished.

When the switch is operated from the open position, as shown in Figure 1, to the closed position, the contact fingers 26 first engage the cylindrical switch member 24, and then the con-

tact fingers 17 engage the U-shaped switch members 16. Because of this sequence of functioning, no arcs are formed between the contact fingers 17 and the U-shaped switch members 16 since the circuit is never completed or opened thereby.

In Figures 6 and 7 of the drawings there is shown a construction which is similar to that shown in Figure 3 of the drawings and in which the present invention is embodied. Mounted on the plate 46 and secured thereto by suitable means is a metallic cup 47 which is adapted to receive the lower end of a corrugated insulator 48 that may be formed of porcelain. The lower end of the insulator 48 is held in position in the cup 47 by suitable cement 49. A deformable washer 50 is provided between the extreme lower end of the insulator 48 and the upper adjacent surface of the metallic cup 47.

The metallic plate 46 is provided with a cylindrical extension 51 onto which a sleeve 52 of insulation is threaded. The extension 51 forms a cylindrical switch member with which contact fingers 53, forming a plug-like movable switch member, are adapted to have contact engagement. The contact fingers 53 are integrally formed with a metallic sleeve 54 and are spring urged radially outwardly by their inherent resiliency. Their outward movement is limited by means of an arcing ring 55 which loosely fits about the upper ends of the contact fingers 53. It will be observed that the metallic sleeve 54 is threaded onto a metallic rod 56 which is arranged to be connected to another terminal of the circuit and is adapted to be moved in a vertical direction by suitable operating mechanism, not shown. A sleeve 57 of insulation surrounds the lower portions of the contact fingers 53 and extends over the rod 56. A nut 58 threaded onto the rod 56 serves to hold the sleeve 57 of insulation in place.

The plug-like switch member formed by the contact fingers 53 is arranged to move longitudinally through a bore 59 that is formed in a sleeve of insulation made up by a stack of fiber rings or washers 60. The sleeve of insulation is made up by the fiber rings or washers 60 for the reasons fully set forth hereinbefore. The stack of fiber washers 60 is enclosed by the sleeve 52 and is held therein in the desired position by means of threaded rings 61 and 62 at its ends.

The rings 55 and 61 form auxiliary arcing contact members between which the arc is drawn on operation of the switch to the open position. They are provided to prevent pitting of the switch members formed by the extension 51 and the contact fingers 53. Since they are subject to erosion due to arcing, they are made so as to be readily replaced. Preferably they are formed of silver tungsten or other arc resisting material.

Mounted on the rod 56 and movable therewith is a stack of fiber rings or washers 65 which form a plug of insulation. The arc that is drawn between the rings 55 and 61 is arranged to be confined between the outer surface 66 of the fiber washers 65 and the bore 59 as previously described. The fiber washers 65 are mounted on a sleeve 67 of insulation which is provided with a flanged head 68 that holds the stack in place. The sleeve 67 is threaded onto an extension 69 which is integrally formed with the rod 56. A metallic washer 70 is provided at the upper end of the rod 56 and underneath the lowermost washer 65 for assisting in holding the stack in place.

The operation of the switch construction shown

in Figure 6 will be essentially the same as that described for the switch construction shown in Figures 1 and 3 and, hence, will not be set forth in detail here.

In Figures 8 and 9 of the drawings still another embodiment of the invention is disclosed. As there shown, a tubular insulating housing 74 is provided and is preferably formed of porcelain. At the ends of the housing 74 line terminals 75 and 76 are provided for connection to line conductors, as will be readily understood. The line terminals 75 and 76 are in axial alignment and carry metallic sleeves 77 and 78 with which are integrally formed contact fingers 79 and 80 that form generally cylindrical switch members. The free ends of the contact fingers 79 and 80 are biased radially inwardly by garter springs 81 and 82. Associated with the cylindrical switch members formed by the contact fingers 79 and 80 are sleeves 83 and 84 of insulating material, such as fiber, from which an arc extinguishing medium is evolved when subjected to the heat of an arc.

It will be observed that the insulating sleeves 83 and 84, as well as the cylindrical switch members provided by the contact fingers 79 and 80, are in axial alignment for receiving a bayonet type switch member shown generally at 88, endwise therethrough. The bayonet switch member 88 is provided with plug-like switch members 89 and 90 at its ends for contact engagement with the adjacent contact fingers 79 and 80 in the switch closed position as shown. The plug-like switch members 89 and 90 are interconnected by a metallic rod 91 which is surrounded by a sleeve 92 of insulating material such as fiber. The plug-like switch member 89 is provided with an extension 93 that is secured to an insulating handle member 94.

Associated with the lower plug-like switch member 90 is a sleeve 95 of insulation such as fiber, which is held in place by a screw 96.

When the handle 94 and the bayonet member 88 attached thereto are withdrawn from the housing 74, it will be observed that the circuit between the terminals 75 and 76 is opened at two points. That is, it is opened between the lower ends of the contact fingers 79 and the plug-like switch member 89, and also it is opened between the upper ends of the contact fingers 80 and the associated plug-like switch member 90. It will be noted that the two arcs thus formed are in series circuit relation. The arc that is drawn between the switch members 81 and 89 is confined between the bore 97 in the sleeve 83 and the outer surface 98 of the sleeve 91. Because of the arc extinguishing material that is evolved from these surfaces and, further, because the arc is confined, its extinction is facilitated. The arc that is formed between the switch members 80 and 90 is likewise confined between the bore 99 of the sleeve 84 and the outer surface 98 of the sleeve 92. In the manner above described, the extinction of this arc is facilitated.

Since certain changes can be made in the foregoing constructions and different embodiments of the invention can be made without departing from the scope thereof, it is intended that all matter shown in the accompanying drawings and described hereinbefore shall be interpreted as illustrative and not in a limiting sense.

What is claimed as new is:

1. In a dry type circuit interrupter, arc extinguishing means comprising a plurality of rings of fiber stacked one above the other and providing

a bore therethrough of substantially uniform diameter in which the arc is drawn.

2. In a dry type circuit interrupter, arc extinguishing means comprising a plurality of rings of fiber stacked one above the other and providing a substantially uniform convex cylindrical surface over which the arc is drawn.

3. In a circuit interrupter, arc extinguishing means comprising a plurality of rings of fiber stacked one above the other so as to provide a cylindrical surface with the grain of the fiber in the rings running substantially at right angles to the longitudinal axis of said cylindrical surface, whereby substantially no transverse expansion takes place and the diameter thereof remains substantially unchanged with variations in moisture content of said rings.

4. In a circuit interrupter, arc extinguishing means comprising a plurality of rings of fiber stacked one above the other so as to provide a bore with the grain of the fiber in adjacent rings running in different directions in planes at right angles to the longitudinal axis of said bore whereby substantially no transverse expansion takes place and the internal diameter thereof is maintained substantially unchanged with variations in moisture content of said rings.

5. In a circuit interrupter, arc extinguishing means comprising a plurality of rings of fiber stacked one above the other so as to provide a convex cylindrical surface with the grain of the fiber in adjacent rings running in different directions in planes at right angles to the longitudinal axis of said cylindrical surface whereby substantially no transverse expansion takes place and the diameter thereof is maintained substantially unchanged with variations in moisture content of said rings.

6. In a dry type circuit interrupter, in combination, a pair of separable switch members between which an arc may be drawn, a sleeve formed by a plurality of fiber rings of uniform internal diameter stacked one above the other and fastened to one switch member, and a plug of insulation fastened to the other switch member, said plug and associated switch member being movable through said sleeve and the arc between said switch members being confined in the space between said sleeve and plug.

7. In a dry type circuit interrupter, in combination, a pair of separable switch members between which an arc may be drawn, a sleeve formed by a plurality of fiber rings of uniform internal diameter stacked one above the other and fastened to one switch member, and a plug formed by a plurality of rings of fiber of uniform external diameter stacked one above the other and fastened to the other switch member, said plug and associated switch member being movable through said sleeve and the arc between said switch members being confined in the space between said sleeve and plug.

8. In a dry type circuit interrupter, in combination, a pair of separable switch members between which an arc may be drawn, one of said switch members being generally in the form of a metallic sleeve and the other being generally in the form of a metallic plug, a sleeve of insulation formed by a plurality of fiber rings of uniform internal diameter stacked one above the other and fastened coaxially to said one switch member, and a plug of insulation fastened coaxially to said other switch member, said other switch member and plug of insulation carried thereby being movable through said switch member and said sleeve

of insulation whereby the arc between said switch members is confined in the space between said sleeve and plug of insulation.

9. In a dry type circuit interrupter, in combination, a pair of separable switch members between which an arc may be drawn, one of said switch members being generally in the form of a metallic sleeve and the other being generally in the form of a metallic plug, a sleeve of insulation formed by a plurality of fiber rings of uniform internal diameter stacked one above the other and fastened coaxially to said one switch member, and a plug of insulation formed by a plurality of fiber rings of uniform external diameter stacked one above the other and fastened coaxially to said other switch member, said other switch member and plug of insulation carried thereby being movable through said one switch member and said sleeve of insulation whereby the arc between said switch members is confined in the space between said sleeve and plug of insulation.

10. In a dry type circuit interrupter, in combination, a pair of generally cylindrical switch members and means for stationarily mounting the same in insulated spaced relation, a pair of plug-like switch members and means electrically connecting and mounting the same for movement into and out of engagement with said generally cylindrical switch members, a sleeve of insulation formed by a plurality of fiber rings of uniform internal diameter stacked one above the other and fastened coaxially to each cylindrical switch member, and a plug of insulation fastened

coaxially to each plug-like switch member, each plug-like switch member and its plug of insulation being movable through the corresponding cylindrical switch member and its sleeve of insulation whereby two arcs are drawn in series and the arc drawn between each cylindrical switch member and the cooperating plug-like switch member is confined in the space between the associated sleeve and plug of insulation.

11. In a dry type circuit interrupter, in combination, a pair of generally cylindrical switch members and means for stationarily mounting the same in insulated spaced relation, a pair of plug-like switch members and means electrically connecting and mounting the same for movement into and out of engagement with said generally cylindrical switch members, a sleeve of insulation formed by a plurality of fiber rings of uniform internal diameter stacked one above the other and fastened coaxially to each cylindrical switch member, and a plug of insulation formed by a plurality of fiber rings of uniform external diameter stacked one above the other and fastened coaxially to each plug-like switch member, each plug-like switch member and its plug of insulation being movable through the corresponding cylindrical switch member and its sleeve of insulation whereby two arcs are drawn in series and the arc drawn between each cylindrical switch member and the cooperating plug-like switch member is confined in the space between the associated sleeve and plug of insulation.

HUGH A. TRIPPLETT.
